*Inventor
Edward A. Johnston*

Thos. E. Lord, my

UNITED STATES PATENT OFFICE.

EDWARD A. JOHNSTON, OF CHICAGO, ILLINOIS, ASSIGNOR TO INTERNATIONAL HARVESTER CORPORATION, A CORPORATION OF NEW JERSEY.

ENGINE.

1,254,699.

Specification of Letters Patent. Patented Jan. 29, 1918.

Application filed February 11, 1915. Serial No. 7,483.

To all whom it may concern:

Be it known that I, EDWARD A. JOHNSTON, a citizen of the United States, residing at Chicago, in the county of Cook and State 5 of Illinois, have invented certain new and useful Improvements in Engines, of which the following is a full, clear, and exact specification.

This invention relates to engines, and 10 more particularly to auxiliary engines for starting larger ones.

The main object of the invention is to control automatically the starting power developed by and transmitted from the starting 15 engine to the larger engine to be started.

Another object is to change the automatic control to manual control, and vice versa, at will.

These objects are accomplished by providing 20 a starting engine with means for controlling the supply of actuating fluid thereto, means for automatically controlling the action of said first means, and means whereby the automatic control can be changed to 25 manual control, and vice versa. The invention is illustrated on the accompanying sheet of drawings, in which—

Figure 1 is a side elevation of a starting engine embodying my invention and showing 30 the fly wheel of a larger engine to be started thereby;

Fig. 2 is a detail sectional view taken along the line 2—2 of Fig. 1; and

Fig. 3 is a fragmentary view of the fuel 35 mixture intake pipe leading to the inlet valve of the engine and showing the general arrangement and control parts of the mixture throttling valve.

The various novel features of my invention 40 will be apparent from the following description and drawings, and will be particularly set forth in the appended claims.

It is a well-known fact that it is a difficult 45 matter to manually start gas engines of large capacity, it being necessary that engines of certain capacity above a certain minimum be started by means of a small auxiliary starting unit. To illustrate my invention, I have shown the fly wheel 10 of a 50 relatively large engine to be started, which fly wheel is engaged under starting conditions by a rotating frictional element 11 of the auxiliary starting engine 12. As shown, this auxiliary starting engine takes the form 55 of an internal combustion engine having a

cylinder 13, to which fuel is supplied through a fuel inlet supply pipe 14, and from which cylinder exhaust gases are expelled in the usual manner when the exhaust valve is mechanically opened through action 60 transmitted from a suitable cam 15, which is securely mounted upon a sleeve portion 16 of a relatively large gear 17, which is driven by a smaller gear 18 mounted upon and secured to the crank shaft 19 of the starting 65 engine. The gear 17, with its sleeve 16, rotates upon a stationary shaft 20, from which it is separated by suitable Babbitt metal 21, said shaft being retained in supporting portions of the engine housing. Mounted upon one portion of the sleeve 16 is a spider frame 22, in which is secured the rotating frictional element 11 and which has projections 23 which interlock with projections 24 of the sleeve 16 by means of which a rotating 70 movement is transmitted from the gear 17 to the rotating frictional element 11.

The auxiliary starting engine 12 as a whole is pivotally mounted at 25 upon a suitable base 26 which, if desired, may be 80 the base of the main engine to be started. The auxiliary engine 12 may be actuated in a manner such that the rotating frictional element 11 thereof may approach and recede from the fly wheel of the engine to be 85 started by means of a hand operated lever 27 pivotally mounted at 28 on an ear 29 on the base 26, said lever having a pivotal connection with an adjustable link 30, one end of which is connected at 31 to a suitable 90 ear formed on the case of the auxiliary engine 12. As shown in Fig. 1, the frictional rotating element 11 is out of engagement with the fly wheel 10 of the engine to be started. The rotating frictional element 11 95 may be pressed into engagement with the fly wheel 10 by raising the lever 27, which will move the whole auxiliary engine bodily about the pivotal point 25, causing the rotating frictional element 11 to engage the 100 fly wheel 10 of the engine to be started. By lowering the lever 27 when the rotating element 11 is in engagement with the fly wheel 10, the whole auxiliary engine as a unit is rotated in a reverse manner about its pivotal point 25, causing the disengagement of the rotating element 11 and fly wheel 10.

Located within the fuel conducting pipe 14 which leads to the cylinder 13 of the auxiliary engine is a mixture throttling 110

valve 35 mounted upon a pin 36, to one end of which is secured an operating handle 37 having an ear 38, to which is secured a link 39, one end of which is connected to one end 5 of a relatively stiff spring 40, the other end of which spring 40 is connected to an adjustable stud 41 mounted in the base 26. Normally the mixture throttling valve 35 is pressed in one of its extreme positions by a 10 properly arranged spring 42, one end of which engages a projection 43 of the handle 37, which projection 43 engages an adjustable stop 44 which limits the closing movement of the mixture throttling valve when it 15 is in one of its normal extreme positions.

When the auxiliary engine is in operation the liquid fuel is drawn from any suitable source 45, by the suction of the engine, through a fuel port 46, which is controlled by 20 a puppet valve 47, which puppet valve also controls the air supply through conduit 48. The mixture, liquid fuel and air, passes up through the pipe 14 and the quantity thereof is controlled by the mixture throttling valve 25 35; that is to say, as the mixture throttling valve 35 is opened more and more, a greater quantity of fuel is permitted to pass the same and into the engine, the explosion of which greater quantity increases the power 30 developed by the auxiliary starting engine. It is of importance that a relatively great power be developed by the auxiliary starting engine when the rotating frictional element 11 engages the fly wheel 10 of the engine to 35 be started. To accomplish this result the connection including the rod 39, spring 40, and stud 41 is provided whereby, when the rotatable friction element 11 is pressed toward the fly wheel 10, by raising the lever 40 27, the mixture throttling valve 35 is automatically opened a greater amount, thereby permitting a greater quantity of fuel to pass into the engine for developing the increased amount of power which is developed in and 45 transmitted from the auxiliary starting engine to the fly wheel of the engine to be started. The quantity of fuel mixture passing the mixture throttling valve 35 may also be controlled manually by actuating the 50 handle 37 regardless of the automatic actuation of the mixture throttling valve to vary the quantity of mixture supply to the engine. Let it be assumed that the rotating frictional element 11 is in engagement with 55 the fly wheel 10 and the mixture throttling valve is opened a certain amount to permit a certain quantity of mixture to be supplied to the starting engine. With these conditions existing, if a greater quantity of fuel 60 mixture is desired, the same is made possible by rotating the mixture throttling valve 35 in the same direction an added amount by properly moving the handle 37. In like manner the quantity of mixture passing the 65 mixture throttling valve 35 may be de-

creased by moving the handle in an opposite direction. It is seen, therefore, that as the auxiliary starting engine is moved toward the engine to be started the developed power of the auxiliary engine is automatically increased, and as said auxiliary engine is moved from the large engine to be started the developed power is decreased; also that the automatic control can be changed into manual control, and the manual control into 70 automatic control at will. 75

It is evident that there may be various modifications of the invention other than that here particularly shown and described, and it is my intention to cover all such modifications which do not depart from the spirit and scope of my invention as set forth in 80 the following claims.

What I claim as new is:

1. In combination, an engine to be started, 85 a pivotally mounted auxiliary starting engine movable toward and from the engine to be started, and means by which the power of the starting engine is automatically increased as it is swung bodily about its pivot toward 90 the engine to be started.
2. In combination, an engine to be started, 95 a pivotally mounted auxiliary starting engine movable toward and from the engine to be started, and means by which the power of the starting engine is automatically decreased as it is swung bodily about its pivot from the engine to be started.
3. An internal combustion engine used for starting purposes and adapted to be 100 moved, said engine having a valve to control the passage of a combustible fuel, and automatic means for varying the opening of said valve to permit a varied quantity of combustible fuel to pass as the engine is moved 105 bodily.
4. An internal combustion engine used for starting purposes and adapted to be moved, said engine having a cylinder, a source of combustible fuel supply, a valve for controlling the supply of combustible fuel from 110 said source to the cylinder, and means whereby said valve is opened automatically as the engine is moved bodily in one direction and moved toward closed position when 115 the engine is moved bodily in another direction.
5. In combination, an engine to be started, 120 a controlled auxiliary starting engine, the developed power of which is automatically varied as the distance between said engines is varied, and means for changing the control from automatic to manual.
6. In combination, a base, an engine pivotally mounted thereon, and means by which 125 the power of the engine is automatically changed as the engine is swung bodily about its pivotal point.
7. In combination, a base, an engine pivotally mounted thereon and having a mix- 130

ture throttling valve, means for swinging said engine about its pivotal point, and means for automatically opening and closing said valve as said engine is moved about its pivotal point.

8. In combination, a base, an engine pivotally mounted thereon and having a mixture throttling valve, a yieldable connection between said throttling valve and said base,

and means for swinging said engine about its pivotal point whereupon said throttling valve is opened at the same time.

In testimony whereof I affix my signature in the presence of two witnesses.

EDWARD A. JOHNSTON.
